Primary Examiner — Keli L Hill(74) *Attorney, Agent, or Firm* — Dorsey & Whitney LLP(57) **CLAIM**

I claim the ornamental design for a bottle, substantially as shown and described.

DESCRIPTION

FIG. 1 is a front isometric view of a first embodiment of a bottle.

FIG. 2 is a front elevation view of the bottle of FIG. 1.

FIG. 3 is a rear elevation view of the bottle of FIG. 1.

FIG. 4 is a right side elevation view of the bottle of FIG. 1.

FIG. 5 is a left side elevation view of the bottle of FIG. 1.

FIG. 6 is a top plan view of the bottle of FIG. 1; and,

FIG. 7 is a bottom plan view of the bottle of FIG. 1.

The broken lines, which define the bounds of the claimed design, form no part of the claimed design.
